CAN PUNCTURING DEVICE

William J. Kershenstein, Detroit, Mich.

Application March 11, 1940, Serial No. 323,373

3 Claims. (Cl. 30—16)

This invention relates to can opening devices and particularly relates to a device for puncturing cans in which liquids are sealed.

In order that liquids may be poured from sealed cans, it is necessary to open the can in such manner that air may enter the can to displace the liquid as the liquid is poured from the can. The common practice is to puncture at least two holes in the top of the can, which holes are preferably oppositely disposed to one another near the outer edge of the can top. This facilitates the removal of the liquids from the can, inasmuch as the liquid can be poured from one hole while the air enters the can through the other hole.

The principal object of the invention, therefore, is to provide a device which will enable the user to puncture such holes in a can top in an efficient manner.

Another object of the invention is to provide a device of the character referred to which is adjustable to cans of different diameters.

Another object of the invention is the provision of a device of the character referred to which is provided with resilient elements adapted to serve as a protective element to the cutting members when not in use, and which serve as stabilizers to the cutting elements at the beginning of the work stroke, and further assist in the removal of the cutting elements from the can after the work stroke has been completed.

A further object of the invention is the provision of a device of the character referred to which is simple in construction, economical to manufacture and one which has a wide variety of applications.

The foregoing and other objects of the invention will be more readily understood as the description proceeds, reference being made from time to time to the accompanying drawing, in which:

Fig. 1 is a fragmentary perspective view of the upper portions of a can which has already been punctured with a device embodying my invention.

Fig. 2 is a vertical sectional view of the device illustrated in Fig. 1 at the completion of the puncturing stroke.

Fig. 3 is a section taken substantially on the line 3—3 of Fig. 2.

Fig. 4 is a vertical sectional view of a modified form of a device embodying my invention.

Fig. 5 is a view taken substantially on the line 5—5 of Fig. 4.

Fig. 6 is a modified form of a device embodying my invention.

Referring now more particularly to the draw-

ing, it will be understood that in general, my improved device consists of a hand grip 8, supporting elements 9 and 9a and puncturing or cutting elements 10 and 10a, arranged as illustrated in Fig. 1. The grip 8 is adapted to rest in the palm of the hand so that the fingers of the operator may extend thereunder and between the end portions of the supporting elements 9 and 9a.

The grip member 8 is provided with tunnel members 11, which extend around the upper reaches of the supporting elements 9 and 9a, the latter being slotted as at 12 to accommodate bolts 13, which pass through the slots 12 and apertures 14 formed in the tunnels 11. The members 9 and 9a are locked in position by means of the wing nuts 15. This arrangement permits the supporting elements 9 and 9a to be adjusted with reference to one another and prevents them from rotating about the bolts 13.

The puncturing or cutting elements 10 and 10a may be of any desired size and shape and may be secured to the supporting elements 9 and 9a in any suitable manner, such as by threads or brazing.

Secured to the underside of the supporting elements 9 and 9a, by any suitable means, are spring members 16 which are adapted to encircle the cutting elements 10 and 10a. The springs 16, in their normal positions, are slightly longer than the cutting elements 10 and 10a, and serve as guards for the sharp pointed cutting elements, when not in use. The free ends of the springs 16 are arranged to contact the can top 17 before the points of the cutting elements strike, thereby providing a comparatively broad contact surface for the device before the cutting elements 10 and 10a commence their work. After the work stroke is completed, the springs 16 serve the further purpose of assisting in the removal of the cutting elements from the can top 17.

Figs. 1, 2, and 3 illustrate the manner in which the can is punctured to provide the dispensing hole 18 and the air intake hole 19. In using the device, the supporting members 9 and 9a are adjusted to the desired position so that the holes 18 and 19 will be properly located. The operator then grasps the device so that the fingers extend around the grip 8 and beneath the upper reaches of the supporting members 9 and 9a. The free ends of the springs 16 are then positioned on the can top 17 and pressure is exerted on the top of the device so that the cutting elements 10 and 10a are forced through the top 17 so that the desired results are accomplished. The cutting elements 10 and 10a are then withdrawn

from the can top, the withdrawal being assisted by the compression of the springs 16, as shown in Figs. 2 and 3.

Although I have illustrated in Figs. 1 to 3 inclusive, the supporting elements 8 and 8a as being adjustable, it is also within the contemplation of the invention to make the supporting members integral with one another as indicated at 9b in Fig. 4. In this embodiment the grip 8 is not a continuous member, but terminates in the ends 8'. These ends are secured to the member 9b by means of rivets 11'.

In this embodiment the cutting elements 10b and 10c are formed integral with the supporting member 9b by stamping sections of the metal from the member 9b as indicated at 20. The stamping operation required to form the cutting elements 10b and 10c would preferably take place while the supporting member 9b is flat and before it is bent into the form illustrated in Fig. 4. In this embodiment the springs 16 are secured to the supporting member 9b by means of ears 21 which are also struck from the supporting member and which are bent as shown in Fig. 4, to engage the springs 16 and to hold them in position.

In Fig. 6 I have illustrated another modification of my device in which the device takes the

form of a single cutting element 22 mounted in the end of a wooden handle 23, and provided with the spring guard 24 which is held in place by any suitable means such as a collar 25.

Having described my invention, what I claim and desire to secure by Letters Patent is:

1. A can punching device consisting of a strip of metal bent to form a loop, there being ears formed on one portion of said strip, said ears being bent and re-bent to form tunnel like members beneath said loop, J-shaped members adapted to engage said tunnel members and punches secured to said J-shaped members.

2. The device defined in claim 1, in which the ends of said J-shaped members which engage the tunnel members are slotted, and the tunnel members have apertures therein in alignment with said slots, there being adjustable locking means extending through said apertures and said slots.

3. The device defined in claim 1, in which the J-shaped members are slotted at one end to engage the tunnel members, and the punches are provided with concentric springs, which said springs in extended position are longer than said punches and serve as guards for said punches when the same are not in use.

WILLIAM J. KERSHENSTEIN.
